UNITED STATES PATENT OFFICE.

LEON TOBIAS, OF NEW YORK, N. Y.

SHAVING-BRUSH.

1,358,597.

Specification of Letters Patent.

Patented Nov. 9, 1920.

Application filed March 22, 1920. Serial No. 367,809.

To all whom it may concern:

Be it known that I, LEON TOBIAS, a citizen of the United States, and a resident of the city of New York, borough of the Bronx, 5 in the county of Bronx and State of New York, have invented a new and Improved Shaving-Brush, of which the following is a full, clear, and exact description.

This invention relates to improvements in 10 shaving brushes, an object of the invention being to provide a shaving brush equipped with the ordinary bristles for forming and distributing lather and also provided with means for rubbing the lather into the face 15 to soften the beard, the parts so constructed and arranged as to permit either the bristles or the rubbing device to be exposed for use at the end of a suitable handle.

A further object is to provide an improved 20 construction of handle having a brush slidably mounted therein so that the latter can be projected from the end of the handle or inclosed within the handle and provide on the end of the handle a rubbing or massaging attachment which is in position for use 25 when the brush is inclosed in the handle.

With these and other objects in view the invention consists in certain novel features of construction, and combinations and arrangements of parts, as will be more fully 30 hereinafter described and pointed out in the claim.

In the accompanying drawings—

Figure 1 is a view in elevation illustrating 35 my invention;

Fig. 2 is a view in longitudinal section; and

Fig. 3 is a view in transverse section on the line 3—3 of Fig. 1.

40 1 represents a cylindrical handle having a knob or closure 2 at one end. Slidably mounted in the handle 1 is a cylindrical carrier or body 3 in which the bristles 4 forming a shaving brush are rigidly secured in any 45 approved manner.

The parts 3 and 4 constitute a shaving brush and the body 3 fits within the handle 1 and is slidably mounted therein so that it can be moved longitudinally either to project the bristles as shown, or when moved to its other extreme position to so position the bristles that they will be entirely inclosed in the handle.

To facilitate and control this movement 5 of the brush I provide screws 5 which are projected through longitudinal slots 6 in the

handle 1 and extend sufficiently beyond the outer surface of the handle to afford a ready grip to allow a free manipulation of the brush. Notches 7 and 8 are provided at the ends of the slots 6 and notches 9 intermediate the ends of the slots 6, so that these screws 5 may be secured in any of these notches. When the screws 5 are in either of the extreme notches 7 or 8, the brush will either be inclosed in the handle or fully projected therefrom, but when the screws are in the intermediate notches 9, the bristles 4 will be but partially projected so as to provide a shorter, more rigid length of bristle which is sometimes desirable in making lather and softening beard.

The open end of the handle 1 is made with an annular flange 10 and this flange supports a ring 11 preferably of soft rubber. The ring 11 is formed with an internal annular groove or recess 12 to receive the flange 10 and said ring is of sufficient elasticity to allow it to be stretched or spread open to receive the flange 10 and will spring into locked position thereon. The ring 11 on its outer face is made with a series of relatively small lugs or projections 13 and may be otherwise surfaced so as to give the desired rubbing or massaging action to rub 85 the beard and the skin so as to soften the beard previous to shaving.

This practice of softening the beard is commonly carried out by rubbing the lather into the face with the fingers and when this 90 operation is performed by a barber or other person, it is extremely unsanitary and more or less dangerous. By providing a device such as above explained, it is not necessary for the barber or other operator to touch the 95 face with his fingers and the massaging and beard softening operation can be easily and quickly performed in a sanitary manner.

Various slight changes might be made in the general form and arrangement of parts 100 described without departing from the invention, and hence I do not limit myself to the precise details set forth, but consider myself at liberty to make such changes and alterations as fairly fall within the spirit 105 and scope of the appended claim.

I claim:

A device of the character stated, comprising a cylindrical handle, an annular flange on the open end of the handle, a closure 110 device on the other end of the handle, said handle having a longitudinal slot and

notches at the ends of the slot and at the intermediate portion thereof, a massage device located on the flange and having a massaging surface at the end of the handle, a brush comprising a cylindrical body fitting the handle and supporting bristles, and a pin projecting from the cylindrical body and through the said slot, said pin adapted to

be operated to move the brush longitudinally of the handle to hold the brush entirely within the handle or to project the brush partially or fully from the handle and to lock the brush in any of said positions by moving said pin in the said notches. ¹⁰
